WELL PUMPING DEVICE

William J. Gourley and Fred H. Barney, Fort
Worth, Tex.

Application September 14, 1934, Serial No. 744,022

5 Claims. (Cl. 74—593)

This invention relates to new and useful improvements in well pumping devices.

One object of the invention is to provide a pumping device having improved means for hooking off and on the power transmission elements.

Another object of the invention is to provide an improved guide mechanism co-acting with a hook-off device so as to properly support the working parts either when active or when dormant.

A further object of the invention is to provide a power transmission and hook-off mechanism involving operating devices making for safety, convenience and adjustability, as well as efficiency in operation.

Another object of the invention is to provide means for supporting the coupling elements when the same are disconnected, so that as said elements continue to reciprocate they will not drag on the ground or other support.

Still another object of the invention is to provide an improved pitman-operated power transmission for pumping a plurality of wells.

25 A further object of the invention is to provide means for coupling and uncoupling the transmission elements arranged to be operated without the necessity of the operator picking up or grasping the elements.

30 A construction designed to carry out the invention will be hereinafter described, together with other features of the invention.

The invention will be more readily understood from a reading of the following specification and 35 by reference to the accompanying drawings, in which an example of the invention is shown, and wherein:

Figure 1 is a side elevation of a power transmission and hook-off mechanism.

40 Figure 2 is a plan view of the same.

Figure 3 is an enlarged side view partly in elevation and partly in section,

Figure 4 is a plan view, one of the guides being shown in section,

45 Figure 4—A is a transverse vertical sectional view taken on the line 4—4 of Figure 3,

Figure 5 is a side view partly in section and partly in elevation showing another form of the invention,

50 Figure 6 is an enlarged view of the same partly in section and partly in elevation,

Figures 7 and 8 are longitudinally cross sectional views of the same,

Figure 9 is a detail of the hook-off,

55 Figure 10 is an enlarged transverse vertical

sectional view taken on the line 10—10 of Figure 7,

Figure 11 is a plan view of still another form of the invention,

Figure 12 is a longitudinal vertical sectional view of the same,

Figure 13 is a transverse vertical sectional view taken on the line 13—13 of Figure 11, and

Figure 14 is an elevation of the stirrup.

Figure 15 is a side elevation of an extension 10 guide,

Figure 16 is a plan view of the same.

Figure 17 is a view of another form of the invention, partly in elevation and partly in longitudinal section,

Figure 18 is a vertical sectional view of the hook-off mechanism,

Figure 19 is a longitudinal cross-sectional view, and

Figure 20 is a transverse, vertical sectional view, through the carriage and frame.

In the drawings the numeral 10 designates an elongated base which may be made of any suitable material, but when placed on the ground is preferably formed of concrete. A flat metal track 11 is mounted on top of the base as is shown in Figures 1 and 2 and may have its ends terminating short of the ends of the base. Upright sills 12 extend on each side of the base in parallel relation at the central portion thereof. Guide members 13 are fastened on top of the sills and thus elevated above the track. These guide members are preferably made of metal channels disposed longitudinally of the sills with the open sides opposite. The ends of the channels are 35 braced by bridle bars 14.

A carriage 15 is arranged to travel longitudinally between the channels 13. This carriage includes a cross shaft 16 carried by a collar 17 which is connected to the end of a pitman 18. 40 A yoke 19 carries ears 20 on its inner ends which are journaled on the shaft 16. An oppositely directed yoke 21 has ears 22 at its inner end journaled on the shaft on each side of the collar 17 and between said collar and the ears 20. Flanged 45 guide rollers 23 are journaled on the ends of the shaft 16 and ride in the channels 13. As is shown in Figure 4—A the wheels travel on the inner bottom flanges of the channels 13, but are confined against upper displacement by the inner top 50 flanges of said channels.

The pitman 18 may be attached to the arm of a crank shaft or any other prime mover whereby a reciprocating movement is imparted to said pitman and the carriage 15 is caused to travel 55

back and forth in the channels. By connecting rod lines to the yokes 19 and 21, it is obvious that two such lines may be operated by the carriage 15.

5 Each yoke is adapted to be connected with a hook-off bar 24 mounted to slide through a knock-off post 25. These posts are spaced a suitable distance from the ends of the base 10 as is shown in Figures 1 to 3 inclusive. Each 10 bar 24 has a plurality of hook-shaped notches 26, one of which is at the inner end of the bar. Each yoke has its outer end reduced and provided with a cross pin 27 which may be engaged in the end notch 26 or one of the other notches 15 if desired. It will be seen that the reciprocating motion of the carriage 15 will be transmitted to the bars 24 by means of the yokes 19 and 21 and said bars thus caused to slide through the 20 posts 25.

20 It is pointed out that should one of the bars 24 be disconnected from its yoke, said yoke being fastened to the shaft 16, would immediately fall thus permitting its outer end to drag on the track 11. In order to support the outer end, each 25 yoke is provided with a depending roller 28 which will travel on the track 11 when the yoke is disconnected. Each yoke also has a handle 29 on one side at its outer end so that it may be safely handled by the operator.

20 Each bar 24 is provided with a head 30 at its outer end whereby it may be clamped to a rod line. When one of the bars 24 is moved inwardly or toward the channels 13, it will exert a pull on the connecting rod coupled thereto which will 35 operate the pump (not shown), whereby the pump rod will be elevated. When the said bar 24 is moved outwardly, the weight of the pump rod will tension the rod line and thus exert a pull on the said bar 24. Each post 25 is provided 40 with a supporting bar 31 fastened on the top of the post and overhanging the bar 24 on the side next to the base 10. A stirrup 32 straddles the bar 24 and has its shank 33 extending upwardly 45 through a hole in the bar 31. A collar 34 fastened on the shank rests upon the bar and suspends the stirrup. The stirrup has a transverse roller 35 at its lower end.

When it is desired to disconnect one of the bars 24 from its yoke the operator grasps the upper 50 end of the shank 33 and elevates the stirrup until the roller 35 engages the lower edge of the reciprocating bar 24. When one of the notches 26 passes over the roller the latter will be pulled into said notch. This is done on the outward 55 stroke of the bar and consequently, when the roller 35 engages in the notch 26, further outward movement of the bar is arrested but the yoke 19 or 21 will continue its outward movement, whereby the pin 27 will be carried out of its notch 60 26, thus permitting the outer end of the yoke to drop and disengage from the bar. The yoke will come to rest on its roller 28 while the pull of the rod line will carry the roller 35 into contact with a post 25. From the foregoing it will be 65 seen that the bar 24 may be disconnected with a high factor of safety and without necessitating the workman endangering any member of his body.

So long as a yoke is disconnected it will be 70 reciprocated by the pitman 18, and its outer end will be supported by its roller 28 which will travel on the track 10. When it is desired to couple the yoke and bar, the operator waits until the pin 27 is under the arrested bar 24, at which point 75 he grasps the handle 29 and swings the yoke up-

wardly until its pin 27 engages the bottom edge of said bar. When the yoke moves inwardly toward the channels 13 the pin will be carried into the end notch 26. When this coupling is effected the bar 24 will be moved inwardly and 5 this will automatically release the stirrup 32, whereby the roller 35 will drop out of its notch. Manifestly, the parts may be coupled in a safe and easy manner.

In Figures 5 to 10 inclusive we have shown another form of the invention. This form includes a longitudinal frame 49 made up of sills 41 and top rails 42 connected and secured to uprights or posts 43, 44, 45, 46 and 47 respectively. The tops of the posts 43, 44 and 45 are connected by cross 15 bars 48. The sills 41 may be made of angle bars, each having one leg turned outwardly at the base and the other directed upwardly as is shown in Figure 10. The top rails 42 are preferably formed of angles each having one leg directed downwardly and the other extending inwardly at the top of the angle.

Each post 43 to 47 inclusive, is preferably made of a channel bar having its bottom resting on the out-turned leg of the sill and its flat side 25 fastened to the flat outer sides of the sill 41 or rail 42. Guide angles 49 are carried by the posts 43, 44 and 45, below and longitudinally of the top rails. The legs of the angles are disposed so as to co-act with the rails and form guide channels for wheels 50 journaled on the cross shaft 51 of a carriage 52 including a collar 53 secured to a pitman 54. The actuation of the pitman 54 parts a reciprocating movement to the carriage.

A yoke 55 has ears 56 at its inner end journaled on the carriage, while a second yoke 57 has ears 58 journaled on the carriage outside of the ears 56. The yokes extend in opposite directions from the carriage within the frame, the yoke 57 being larger and longer and underlying the pitman 54. It is desirable to limit the vertical play 40 of the wheels 50 and to accomplish this, those portions of the top rails 42 overlying the guide angles 49 are made vertically adjustable to compensate for wear and irregularities in the frame. 45

Cross members 59 secured between the posts 43, 44 and 45 have inclined bottoms for receiving wedges 60 riding on the top rails 42. These wedges are slid by screws 61 threaded through lugs 62 fastened on said rails. The rails (Figure 50 6) have vertical slots 63 receiving bolts 64 carried by the posts 43, 44 and 45. By loosening the bolts and adjusting the wedges the rails 42 may be adjusted with relation to the wheels 50.

Each yoke has a cross pin 65 (Figure 9) at its 55 outer end provided with inclined spaced bosses 66. These bosses act to displace the hooks 67 on the bottom of a coupling or knock-off bar 68, into engagement with the pin when the yoke is swung upwardly to couple it to said bar. Below the 60 bosses 66, each yoke has a depending roller 69 located to travel on a track 70 (Figures 5, 6 and 9). In order to hold the yoke and bar in engagement a latch pin 71 is passed through ears 72 on the upper edges of the yoke. By withdrawing 65 the pin the yoke may be swung downwardly when the track is lowered.

For raising and lowering the track 70 a pair of rock shafts 73 are journaled in the sills 49 and links 74 fastened on these shafts pivotally support 70 the track. A lever 75 secured to the shaft adjacent each post 47 is used to swing said shaft and thus raise and lower the track. When the track is raised the links and lever are thrown past the perpendicular and the outer end of the 75

track engages a stop 76 carried by the posts 47 (Figures 5 and 6). Suitable latches 75' mounted on the top rail 42 are swung around the levers to hold them in their upright positions. When the lever is swung down to lower one of the tracks it engages in a keeper 77, carried by one of the sills. It will be seen that the outer end of each yoke 55 and 57 is supported on a track at all times.

10 The end posts 47 not only serve as guides for the bars 68, but also as knock-off posts. The posts at each end of the frame are connected by a cap plate 78 and a cross bar 79 between which the bar 68 at that end slides. The cross bars 79 carry the stops 76 and wear blocks 80 on which the bars 68 slide. The bars 68 are maintained in alignment by upright guides 81 (Figures 6 and 7) fastened between the bars 79 and the plates 78. When the carriage 52 is reciprocated the bars 20 68 will be slid between the guides 81.

When it is desired to disconnect one of the bars 68 from its yoke or to engage the pin 65 with another hook 67, to take up slack or relieve tension in the rod line to which the bar is connected, it is necessary to arrest the bar during its outward stroke. A stirrup 82 similar to that shown in Figure 14 is provided for each coupling bar 68. Each stirrup includes a cross roller 83 journaled between the legs of the stirrup and adapted to engage in the hooks 67 and bear against the vertical edges of the guides 81. The legs of the stirrup slide vertically through the stop 76 and a keeper 84 carried by the cap plates 78. The top of the stirrup has a single shank 85 serving as a handle.

It is desirable to operate the stirrup in conjunction with the track 70 and therefore a lever 86 is rested intermediate its ends on the rock shaft 73 adjacent each stirrup so that the lower ends of the stirrup legs rest on the outer end of the lever. The inner end of each lever is loosely mounted on a pin 87 carried by the overhanging track 70. When the lever 75 is swung to lower the track the lever 86 will be swung from the position shown in Figure 6 to the position shown in Figure 9, whereby the stirrup will be elevated. When the track is raised the stirrup will be lowered.

By removing the pin 71 and swinging the lever 75 to the lower track 70, at the end of the frame 40, during the outward stroke of the coupling bar 68, the track 70 will be lowered and the stirrup 82 will be elevated. When the roller 83 rides into one of the hooks 67, further outward movement of the bar will be stopped, whereby the yoke 55 or 57 will continue to move outwardly which will result in the pin 65 dropping out of its hook 67. This uncoupling operation will be accomplished simply by swinging the lever 75 and without handling either bar 68 or the yoke. Coupling is accomplished by raising the track during the inward stroke of a yoke.

This type of apparatus is particularly advantageous where it is desired to operate opposing rod lines and maintain a straight-line motion. The yokes 55 and 57 will be reciprocated by the carriage 52 and the rollers 69, traveling on the tracks 70, will support said yokes in the line of travel. The knock-off bars 68 will be caused to travel in straight lines because of their guides 81 and the attachment to the yokes. The hooks 67 provide adjustments, whereby slack in the rod lines may be taken up.

It is obvious that considerable friction is eliminated in the operation of this device. The wedges

60 take up wear in the guides, thereby limiting the vertical play of the wheels 50. The pins 71 prevent unintentional disconnection of the bars 68 from the yokes.

Safety and convenience are paramount in the 5 operation of the knock-off features. When it is desired to disconnect one of the bars 68, the pin 71 is first withdrawn and then during the outward stroke of said bar, the latter being under the tension of the rod line, the operator merely 10 has to swing the lever 75 from the position shown in Figure 6 to the position shown in Figure 9. This causes the track 70 to be lowered and the stirrup 82 to be elevated, whereby the roller 83 is brought into the path of the hook 67. Just as 15 soon as the roller rides into one of the hooks the outward travel of the bar 68 will be arrested, but the yoke 55 or 57 continuing its outward stroke will carry its pin 65 out of the notch 67, thus permitting the outer end of the yoke to drop until 20 its roller 69 engages the track 70. The bar 68 will be held in its arrested position while the yoke continues to reciprocate, its roller traveling on the track and thereby preventing dragging.

When it is desired to couple one of the bars 68 25 with its yoke 55 or 57 the operator merely has to swing the lever 75, during the inward stroke of the yoke, from its position in Figure 9 to its position shown in Figure 6. This operation will lower the stirrup 82 and raise the track 70, where- 30 by the pin 65 will engage in one of the hooks 67 and impart inward movement to the bar 68. This will release the roller 83, whereby the stirrup will drop. The coupling operation is finished by inserting the pin 71 in the ears 72.

Figures 11 to 14 inclusive show another form of the invention, which is particularly adapted to be used in connection with a pumping power rather than a crank and pitman. Opposed guide channels 90 are set in a concrete base 91 at a height 40 such as to align with the pull rod and the rod line. The base is channeled between the guides to receive a carriage 92 formed of top and bottom plates 93 having horizontal guide wheels 94 journaled between their ends and rolling in the guides 45 90.

A flat pull bar 95 has a collar 96 at its inner end pivoted on a pin 97 fastened in the center of the carriage between the wheels 94. This permits the bar, which is turned on its edge to swing 50 from side to side, while the carriage is traveling between the guides. A knock-off or coupling bar 98 normally aligned with the bar 95 has its inner end rigidly fastened in the carriage between the plates 93, by welding or otherwise. This bar has 55 hooks or notches 99 in the under edge. The guides 90 extend from the base 91 and their outer ends are supported by posts 100. This provides a long travel for the carriage.

Near the outer ends of the guides and relatively 60 between the same a knock-off post 101 is mounted. This post is slotted to permit the bar 98 to slide therethrough. A stirrup 102 straddles the bar 98 and has a roller 103 journaled therein for engaging in the hooks 99. The legs of the stirrup 65 slide through guide arms 106 secured to each side of the post and also adjacent to upright abutments 105 against which the roller rests when in one of the hooks 99. The shank 104 of the stirrup is slidably confined in a guide bar 107 mounted on top of the post 101. A bell crank lever 108 pivoted in a bracket 109 has its short leg pivoted to the shank to raise and lower the stirrup. A counterbalancing weight 110 is mounted on the long leg of the lever for supporting the stirrup 75.

in its elevated position when the said leg is swung past the perpendicular. The operation of this device will, it is believed, be clear from the descriptions of the other forms.

5. While any coupler may be employed to connect the outer end of the pull bar 95 with the pull rod, that shown in Figures 11 and 12 is satisfactory. A coupler link 111 is provided with ears 112 pivoted on a bolt 113 passing through the end of the bar. A stop loop 114 made integral with the ears underlies the bar and engages the lower edge thereof when the link swings downward, thus limiting such swing. A handle 115 has its lower hooked end and secured to the ears, whereby the link may be swung upwardly. A hook 116 on the end of the pull rod (not shown) is engaged by the link to effect the coupling.

It may be desirable to extend the channels 13 or 90, or the guide members 42 and 49 beyond 20 the knock-off post and to support the outer end of the knock-off bar between these extended guides to provide either a hold down or a hold up support for the rod lines. In Figures 15 and 16 such an extension is shown. As a matter of convenience, the channels 90 of the forms shown 25 in Figures 11, 12 and 13 have been extended and these extensions are numbered 90', however it is to be understood that this extension may be applied to any of the other forms. The bar 98 is 30 elongated and extends for some distance beyond the post 101 between the channels. The outer end of the bar is carried on an axle 120 which has flanged wheels 121 journaled on its end and supported by the channels 90'. A connecting clevis 35 122 is pivoted on the axle and has the usual rod connection 123 which may be clamped to the rod line. It will be seen that the rod 98 will be maintained in a straight line, but the clevis will permit the rod line to incline either upwardly 40 or downwardly. The outer ends of the channels 90' may be supported on a prop 124. This extension may be advantageously used where the guides are mounted on top of a hill or in a valley.

The plurality of hook-notches in the sliding 45 bars of each of the structures not only provide for easy and rapid coupling and uncoupling, but further minimize the loss of time and lessen the work in making repairs when the rod lines break. When a pull rod line breaks, especially a long line 50 with a heavy load, the ends of the break will separate from five to ten feet. In making the repair, it usually requires a set of rope blocks or some light weight piece of equipment for pulling the ends together. When the ends are ready to 55 be connected after the break, it is necessary to pull the line back toward the power, as it was necessary to disconnect the pull rod line at or near the power, usually at the knock-off post, so as to obtain slack in the rod line in order to 60 make the connection.

It is obvious that by merely changing the connection of the carriage in the various notches of the sliding bars, it is possible to gain sufficient slack in the line to repair the same after a break. 65 The notches provide for a longitudinal movement of the rod line with disconnection from the carriage. After the break is repaired, the carriage may be connected in the desired notch and the well pumping operation resumed without delay. 70 In Figs. 17 to 20 inclusive, I have shown another form of the invention similar to that shown in Figs. 5 and 6. This form has a longitudinal frame, 130, made up of sills 131 and top rails 132, connected and secured to uprights 133, 134, 135, 75 and 136 respectively. The tops of the posts 133

and 134 are connected by cross bars 137. The sills 131 may be made of angle bars, each having one leg turned outwardly at the base, and the other directed upwardly, as in Figs. 5 to 10. The top rails 132 are preferably formed of angles, 5 each having one leg directed upwardly and the other extending inwardly at the bottom of the angle.

Each post 133 to 136 inclusive, is preferably made of a channel bar having its bottom resting 10 on the out-turned leg of the sill and its flat side fastened to the flat outer sides of the sill 131 and the rail 132. Guide rails 138 and 139 are carried by the posts 133 and 134 and have their treads directed toward each other, as is shown in Fig. 20. 15

The guide rails are so arranged as to form guide channels for flanged wheels 140 traveling therebetween, and journaled on a cross shaft 141 of a carriage 142, including a collar 143 secured to a pitman 144. The actuation of the pitman im- 20 parts a reciprocating movement to the carriage.

The yoke 145 is pivoted on the cross shaft 141, while a second yoke 146 is also pivoted on the carriage 142, and these yokes extend in opposite directions on opposite sides of the carriage with- 25 in the frame. The yoke 145 is larger and longer, and underlies the pitman 144. This yoke 145 is provided with extensions 147 on each side of the yoke 146, and these extensions carry rollers 148. Counter-balances 149 are fastened on the ex- 30 tremities of the extensions and tend to swing the opposite end of the yoke upwardly, whereby said end is elevated. The rollers 148 travel on the lower guide rails 138 and thus support the yoke in this position. 35

The yoke 146 is provided with extensions 150 within the yoke 145, having counter-balances 151 on their extremities. These counter-balances tend to swing the opposite end of the yoke upwardly and this upward movement is limited by 40 stop fingers 152 carried by the extensions 150, and engaging on the side bars of the yoke 145 to limit the swing of the yoke 146. By this arrangement, the outer ends of the yokes are held in their elevated positions when the device is uncoupled. 45

As the coupling or knock-off means at each end of the frame is substantially the same, a description of one will explain both. For each yoke a sliding coupling, or knock-off bar, 153, is provided. This bar has hook notches 154 in its upper 50 edge similar to the bars in the other forms, the difference being that the notches are in the upper edge instead of the lower edge. These notches are adapted to engage the end of the yoke, as is shown in the drawings, and thereby effect a coupling. The posts 136 are connected by a cap plate 155 and a cross bar 156. The bar 153 slides between upright guides 157 fastened between the bar 156 and the cap 155. A wear block of wood or other material 158 is placed between the guides 60 and carried by the bar 156. The coupling bar 153 slides upon this block and by applying grease to the surface thereof a long wear will be obtained. 65

So long as the slide bar 153 is under tension, the yoke will remain in engagement with one of the notches 154, but if the outward movement of the bar 153 is arrested, the continued outward movement of the yoke will cause the yoke to ride out of the notch, and when this occurs, the end of the yoke will swing upwardly as has been previously described, thus taking it out of the path of the notches. For arresting the slide bar, an inverted stirrup 159 is provided. This stirrup straddles the bar 153 and carries a rounded cross bar 160 adapted to engage in the notches 154. 70 75

The ends of this rounded bar travel in vertical guides 161 carried by the cap 155 and the cross bar 156.

When the stirrup is down, the bar 160 will engage in the notches 154. For elevating this stirrup, a rock shaft 162 is mounted in brackets 163 on the sills 131. This shaft is actuated by a lever 164 at one side of the frame. Arms 165 carried by the shaft are pivotally connected with the lower ends of the stirrup. These arms may be counter-balanced if desired. By swinging the lever, 164, it is obvious that the shaft 162 will be rocked and the stirrup raised and lowered. Each yoke may have a handle 170 on its outer end 15 for swinging it downwardly to effect a coupling. It is believed the operation will be clearly understood from the previous explanations given in connection with the other forms of the invention.

20 What we claim and desire to secure by Letters Patent is:

1. In a well pumping device, a guide, a reciprocating carriage mounted in said guide and arranged to travel longitudinally thereof, oppositely extending yokes pivoted to said carriage, and knock-off bar having notches for engaging with the outer ends of said yokes.

2. In a well pumping device, a guide, a reciprocating carriage mounted in said guide and arranged to travel longitudinally thereof, oppositely extending yokes pivoted to said carriage, knock-off bars having notches for engaging with the outer ends of said yokes, knock-off posts for guiding the bar, and knock-off stirrups co-acting with the posts for engaging the notches in the bars.

3. In a well pumping device, elongated guides, a carriage reciprocating in said guides, oppositely

extending yokes having their inner ends pivoted to said carriage, supporting rollers on the outer ends of the yokes, a track below said rollers, and hook-off bars connected with said yokes.

4. In a well pumping device, a guide, a reciprocating carriage mounted in said guide, and arranged to travel longitudinally thereof, a counter-balanced yoke pivoted to and extending longitudinally of said carriage and arranged so that its outer ends will swing upwardly when released, a sliding coupling bar having notches in its upper edge for engaging with the swinging end of the yoke, a guide for the coupling bar, and a stirrup having means for engaging in one of the notches of the bar and co-acting with the guide to arrest said bar.

5. In a well pumping device, a stationary support, a horizontally opposed parallel pair of elongated guides rigidly mounted on said support and each including upper and lower longitudinal members spaced apart, a carriage reciprocating between the guides and having a supporting roller at each side engaging peripherally in the adjacent guide between the upper and lower members thereof, whereby the carriage is retained against lateral movement and is given sufficient play to move freely, and also whereby minimum contacts between the carriage wheels and their supports are provided, an upright knock-off post, a bar slidable through the post and having notches in one of its edges, means pivoted to the carriage and engaging a notch in the bar, a knock-off stirrup co-acting with the post for engaging in a notch of the bar to permit said means to become disengaged therefrom. 35
